UNITED STATES PATENT OFFICE

GEORGE DECKER, OF CLEVELAND, OHIO, ASSIGNOR TO THE PHILAD COMPANY, OF CLEVELAND, OHIO, A CORPORATION OF OHIO

APPARATUS FOR HAIR WAVING

Application filed June 5, 1929. Serial No. 368,544.

This invention relates to apparatus for therefrom and so tightly seal the clamp about use in conjunction with waving hair upon the strand of hair and prevent the metal from touching the hair. On the underside of each

An object of the invention is to provide an improved means for retaining a coiled strand of hair during a waving process.

Another object is to provide a means for holding the hair in coiled stressed condition to a point very near the scalp of the wearer during the process.

Other objects will hereinafter appear.

The invention will be better understood from the description of one practical embodiment thereof, illustrated in the accompanying drawing, in which;

Figure 1 is a perspective view of the protector or clamp used to engage a strand of hair adjacent its roots, showing the protector in open condition;

Figure 2 is a plan view of the protector when closed;

Figure 3 is an end elevation of the protector;

Figure 4 is a cross sectional view thereof taken on line IV—IV of Figure 2;

Figure 5 is a side elevation of the protector together with the curler rod on which the hair is wound;

Figure 6 is an elevation of the curler rod alone;

Figure 7 is a diagrammatic end view of the apparatus of Figure 5; and

Figure 8 is a view similar to Figure 7 showing the positions parts would occupy in the absence of the cradle members.

As most clearly shown in Figures 1 to 4 of the drawing, the clamp consists of two arms pivotally connected at one end and detachably connected at the other, the arms being adapted to tightly grip a flat strand of hair closely adjacent the scalp of the wearer. The arms are shown as consisting of channel-shaped bars 1 and 2, pivoted together at one end by means of rivet 3 and detachably connected at the other end by means of a latch 4.

The open sides of the channels face each other and secured within them are shallow channel-shaped holders 5 in which are mounted strips of rubber 6 which project

bar is secured a strip of heat insulating material 7 shown as of felt or like fibrous substance, secured to the bars by means of rivets

8 or the like, the rivets connecting the fibrous material to downwardly struck projections, as most clearly shown in Figures 1, 3 and 4.

On the upper surface of each bar adjacent

each end is a saddle or cradle-like member 9 shown as of somewhat triangular shape, for a purpose to be hereinafter described.

An L-shaped spring 10 has one leg 11 extending within one of the channels and se

cured to the web thereof by a rivet 12, the other leg 13 extending upwardly and being formed with a projecting tooth or detent 14 for engaging the curling rod.

The rod consists of a tubular shell 15 substantially the shape of the hyperboloid of revolution and having cylindrical ends, being smaller in the middle than at the ends. To

this is pivoted, by means of a rivet 16, a tongue 17 arranged to lie closely adjacent the

surface of the rod, clamping the ends of a together with the curler rod on which the strand of hair thereto. One end of the rod is provided with a series of axially extend-

ing slots 18, positioned to be engaged by the detent carried by the protector.

The operation of the apparatus is as follows: The hair is divided into flat strands and

each one of these has a protector or clamp applied thereto adjacent its roots, the parts of the protector being secured together by

means of the latch 4. The ends of the strand are then placed over the curler rod 15 and

under the tongue 17 and the rod is rotated by the operator to wind the hair spirally upon

it, turn over turn, until the rod is brought down closely adjacent the protector. When

the rod contacts the protector, it is seated upon the cradles 9 thereof, which centers it

upon the axis directly above the opening through the clamp through which the strand passes. The spring 10 presses its detent 14

into engagement with the slots 18 at the end of the rod and the operator can now further

rotate the rod to tension the hair upon it, the slotted end of the rod and the detent acting

100

as a ratchet and pawl to permit the rotation of the rod in one direction and to prevent its return in the other. When the hair has been sufficiently tensioned it is covered by an absorbent pad of flannel or other suitable covering containing any desired treating solution, a heater is applied over the wrapped wound strand, and heat is supplied for the time necessary to impart the desired wave.

10 It will be observed that by maintaining the rod centered above the slot in the clamp, the hair is wound about the rod from a point substantially on the level with the top of the channel-shaped bars as shown in Figure 7, 15 while if the rod were allowed to move laterally, as it would in the absence of the cradle members, it would, due to the tension of the hair, move to the left, as shown in Figure 8, until the hair passed straight upwardly tangentially to the rod. The hair would then 20 start to pass about the rod on a level with the rod's axis, and the part indicated at 19 would be straight and consequently would not be properly waved. By holding the rod 25 in the proper centered position substantially a quarter of a turn more of hair is held wound and tensioned about it, thus causing the wave to be effected that much nearer to the scalp of the subject than would be the case in the 30 absence of the centering device.

While I have described the illustrated embodiment of my invention in some particularity, obviously many others will readily occur to those skilled in the art to which it 35 appertains, and I do not, therefore, limit myself to the precise details shown and described, but claim as my invention all variations, modifications and embodiments thereof coming within the scope of the appended 40 claims.

I claim:

1. Hair waving apparatus including a clamp and a rod, the clamp being arranged to grip a flat strand of hair adjacent the scalp 45 of the wearer and comprising two channel-shaped members having their recessed sides opposed to each other, said members being pivotally connected at one end, a detachable latch connecting said members at the other 50 end, a strip of insulating material secured to the underside of each member, a strip of resilient material received within and extending from the recess of each channel, cradles 55 projecting above and carried by the upper surfaces of said channels, an L-shaped spring having one leg secured to the web of one of said channels and having the other end extending upwardly and provided with a detent, a curler rod of substantially hyperboloid 60 of revolution shape provided with a pivoted tongue, and a ratchet formed on said rod adjacent one end and adapted to be releasably retained by said detent.

2. Hair waving apparatus comprising a 65 clamp engaging a flat strand of hair adjacent

the scalp of the wearer, a rod upon which the hair is wound from its ends to adjacent the clamp, cradle sections carried by the clamp adjacent its ends and engaging the ends of the rod to maintain the same in alinement with the space through the clamp through which the hair extends, and a pawl and ratchet interposed between the rod and clamp to permit rotation of the rod in one direction and prevent it in the other.

3. Hair waving apparatus comprising a clamp having tubular arms pivoted at one end, means for connecting the free ends of said arms to grip a strand of hair, a curler rod upon which the strand of hair may be wound and adapted to be positioned upon the top of the clamp, a ratchet formed in one end of said rod, an L-shaped spring having one leg formed into a pawl to engage the said ratchet, and the other leg extending within one of said tubular arms and having its end secured thereto.

In testimony whereof I hereunto affix my signature this 3rd day of June, 1929.
